ADJUSTABLE COUPLING DEVICE

Arthur E. Dowell, III, Washington, D. C., assignor
to Westinghouse Electric Corporation, East
Pittsburgh, Pa., a corporation of Pennsylvania

Application April 13, 1948, Serial No. 20,686

2 Claims. (Cl. 171—119)

1

My invention relates to adjustable coupling devices for radio circuits and in particular relates to a combined transformer and inductor coil for coupling the output circuit of a balanced mixer with the input of a push-pull amplifier.

So-called balanced-mixer circuits are employed in the radio art where a carrier frequency and a modulated frequency are being impressed on the grids of a mixer tube in order to produce an output having carrier frequency modulated in accordance with an input signal or the like. In one convenient form of the circuit for this purpose, a pair of multi-grid tubes are used, the carrier frequency being impressed on the grids of the two tubes in parallel and the modulating frequency being impressed on the other pair of grids in push-pull. When this is done, the carrier frequency will cancel itself out if the output circuits of the two tubes are likewise arranged in push-pull, so that only the two side-band frequencies are impressed on a load circuit energized therefrom. The undesired side band can then be substantially suppressed in the load circuit by tuning the latter to the desired side band. One convenient way of arranging the output circuits of such a pair of tubes is to provide an inductive winding in series with the anode of each of the above-mentioned push-pull tubes which acts as the primary winding of a transformer, this primary winding being in inductive relation to a secondary winding which is connected to the grids of a push-pull amplifier.

One object of my invention is accordingly to provide a convenient structure embodying the two primary windings and secondary windings above mentioned.

Another object of my invention is to provide a structure embodying the two primary windings and secondary windings above mentioned with a pair of magnetic cores, such that the inductive effect of the two primary windings on the secondary winding can be accurately balanced against each other for the currents of carrier frequency.

Another object of my invention is to provide a structure of the type just mentioned in which the leakage inductance of the secondary winding may be varied at will.

Still another object of my invention is to provide a transformer structure comprising a pair of primary windings and a secondary winding in which the relative inductive effect of the primary windings on the secondary winding, and the self-inductance of the secondary winding, may be varied independently of each other.

2

Other objects of my invention will become apparent on reading the following description taken in connection with the drawing, in which:

5 Figure 1 is a schematic diagram of a balanced mixer and amplifier circuit embodying a transformer made in accordance with my invention; and

Fig. 2 is a diagrammatic showing of a longitudinal section of a transformer structure in accordance with my invention.

Referring in detail to Fig. 1, a pair of similar multi-grid tubes 1 and 2 are arranged to have a carrier frequency input voltage impressed on similar grids of respective tubes in multiple of each other by a carrier voltage source 3. The other grids of the respective tubes 1 and 2 are connected to the opposite ends of the secondary windings 4 and 5 of a push-pull input transformer which derives modulating frequency voltage from a primary winding 6. The plate circuits of the tubes 1 and 2 are respectively connected to the opposite terminals of a pair of primary windings 7 and 8, which are connected to oppose each other in magnetic effect on a secondary winding 9. The adjacent terminals of the windings 7 and 8 are connected together to the positive terminal B+ of a direct-current voltage source (not shown) having its negative terminal connected through the ground to the two cathodes of the tubes 1 and 2. The terminals of the secondary winding 9 are shunted by a variable capacitor 11 and are respectively connected to the control grids of a pair of push-pull amplifier tubes 12 and 13 connected to supply energy in push-pull to a load 14. The cathodes of the tubes 12 and 13 are connected through ground to the midpoint of the secondary winding 9.

The windings 7, 8 and 9 above described may be mounted, in accordance with my invention on a cylinder 21 of insulating material as shown in detail in Fig. 2. The cylinder 21 is preferably enclosed in an aluminum casing 22 having at one end a terminal board of insulating material supporting connection-terminals 23 to 28, inclusive, by which the windings 7, 8 and 9 may be connected into the circuit, as is shown in Fig. 1. The cylinder 21 may conveniently be held in place in the casing 22 by gripping a portion of the latter between a shoulder 29 on the cylinder 21 and a nut 31 making threaded engagement with the outer end of the cylinder 21.

In the hollow interior of the cylinder 21 there projects a second cylindrical member 32 which may be of suitable insulating material and which is supported coaxially with the cylinder 21 by

making threaded engagement with the end portion thereof near the shoulder 29. The cylindrical member 32 is slightly smaller than the cylindrical member 21 so that it can be moved longitudinally thereof by the action of its threaded engagement therewith when it is turned about the common axis by any suitable tool applied to its projecting end. The cylindrical member 32 is hollow and has fastened inside its end remote from its threaded engagement with cylinder 21 a core 33 of powdered magnetite or other suitable magnetic material. The winding 8 is positioned on the outside of the cylinder 21 in a position which is symmetrical relative to the ends of said magnetic core 33.

Separated from the magnetic core 33 within the cylinder 32 is a second core 34 of some similar magnetic material which is of such diameter as to slide readily along the axis of the cylinder 32. A screw 35 threaded into the end of the cylindrical member 32 engages the core 34 and may conveniently be used to displace the core 34 axially along the cylindrical member 32 for regulating purposes which will be described below.

The winding 9 is positioned on the exterior of the cylindrical member 21 in such a position that the cores 33 and 34 are somewhat displaced laterally from its opposite faces, and the windings 7 and 8 are symmetrically placed relative to the winding 9. The core 34 is then given a preliminary adjustment to a position in which its ends project in opposite directions from the opposed end-faces of the winding 7.

As shown in Fig. 2, the similar terminals of the windings 7 and 8 are connected to the terminal stud 26 which is adapted to be connected to the battery terminal B+ in Fig. 1. The other ends of the windings 7 and 8 are respectively connected to the terminal pins 23 and 25 on the terminal board from which they may be respectively connected to the anodes of the tubes 1 and 2 in Fig. 1. An intermediate point on the winding 9 is connected to the terminal stud 27 from which it is adapted to be connected to ground, as shown in Fig. 1. The opposite ends of the winding 9 are then respectively connected to the terminal studs 24 and 28 from which connections may be made to the grids of the amplifier tubes 12 and 13 shown in Fig. 1.

It will be observed that by turning the screw 35, the air gap between the magnetic cores 33 and 34 may be varied at will, thus varying the amount of magnetic coupling between the coils 7 and 8 on the one hand and the secondary winding 9 on the other. Such a variation of the position of the cores 33 and 34 varies the leakage inductance of the winding 9 and makes it possible to thereby assist in tuning the frequency of the resonant circuit comprising winding 9 and capacitor 11. On the other hand by turning the cylindrical member 32 relative to the cylinder 21,

the cores 33 and 34 may be displaced along the common axis of the two cylinders, thereby increasing the inductive effect on the secondary winding 9 of one of the primary windings 7 and 8. The structure I have described therefore makes it possible to adjust the coupling of the windings 7 and 8 to the winding 9 in such a way as may be required to cause the inductive effects of the carrier frequency current flowing in the windings 7 and 8 to neutralize in the winding 9; and at the same time to vary the leakage inductance of the winding 9 to tune it with the capacitor 11 to a desired side-band frequency.

I claim as my invention:

15. 1: A variable transformer comprising a secondary winding supported on an insulating frame, a pair of primary windings spaced apart from said secondary winding on opposite sides thereof on said frame, a support member for a pair of magnetic cores within said frame, one of said cores being affixed to said support member and positioned within one of said primary windings, the other of said cores being slidable along said support member in an axial direction in a region adjacent to the other of said primary windings, means to variably displace said support member axially with respect to said frame and means to displace said slidable core member relative to said support member.
20. 2. A radio transformer comprising an insulating hollow cylinder supporting on its external surface a secondary winding and a pair of similar primary windings displaced axially of said cylinder from opposite faces of said primary winding, a cylindrical member of insulating material coaxial with the first mentioned cylinder and making threaded engagement for displacement along the axis thereof, a first magnetic core affixed to said cylindrical member and aligned
25. 35. 30. 35. 40. 45. with one of said primary windings, a second magnetic core slidable within said cylindrical member in a region adjacent said other primary winding, and means making threaded engagement with said cylindrical member for displacing said second magnetic member axially of said cylindrical member.

ARTHUR E. DOWELL, III.
